ROBERT CARL RAHM, OF WYOMISSING BOROUGH, PENNSYLVANIA, ASSIGNOR TO
TEXTILE MACHINE WORKS, OF WYOMISSING, PENNSYLVANIA, A CORPORATION
OF PENNSYLVANIA.

MOLD-FEEDING ATTACHMENT FOR BRAIDING-MACHINES.

1,161,075.

Specification of Letters Patent. Patented Nov. 23, 1915.

Application filed January 10, 1913. Serial No. 741,159.

To all whom it may concern:

Be it known that I, ROBERT CARL RAHM, a citizen of the United States, residing at the borough of Wyomissing, in the county of Berks and State of Pennsylvania, have invented certain new and useful Improvements in Mold-Feeding Attachments for Braiding-Machines, of which the following is a specification.

10 My invention relates to braiding machines, and consists in an attachment adapted to automatically feed ornamentally shaped forms of wood or the like to the braiding material so as to produce "mold braids" such as are employed for umbrella tassels and various other purposes.

The invention is fully described in connection with the accompanying drawings and is specifically pointed out in the subjoined claims.

Figure 1 is a partial elevation showing my invention in preferred form, as adapted to a known form of tubular braider which is only indicated so far as required to make clear the relative arrangement. Fig. 2 is a view taken at right angles to Fig. 1.

The drawing illustrates my invention as applied to that type of tubular braiding machine in which the braided fabric is taken-off downwardly, which permits of the molds being fed to the braiding point of the machine from a centrally arranged mold container above said point.

The central container consists, as shown, of a vertically arranged feed tube 3 which is adjustably secured at 4 to a transverse carrier bar 5 supported upon standards 6 on the top bed plate 7 of the machine. The braiding threads 8 pass from the carriers 9 to the braiding point over the edges of the braiding cup 10, and the finished braid is drawn downward through the tube 11 by suitable take-off mechanism; which latter and other well known portions of the machine it is unnecessary to describe.

The molds employed, one form of which is shown at 15, are generally provided with an axial opening, and in the preferred construction shown I provide a wire supporting stem 16, upon which they are conveniently strung; the lower end 17 of said wire being forked to form a collapsible tip which normally retains the molds thereon but permits

of their being readily forced off as herein-after described. This mold supporting stem 55 is placed in the feed tube 3, and supported thereon by a collar 18 so as to extend below the enlarged lower end 19 of said tube, approximately to the braiding point of the machine as indicated. 60

Sliding upon the feed tube 3 is a sleeve 20, to the lower end of which are pivoted at 21, 21, coöperating mold-feed fingers 22, 22, which are normally pressed-together by springs 23 so as to bring their depending 65 tips 24 into engagement with a mold upon the depending stem when the sleeve is in lowered or partially lowered position upon the tube 3. When the sleeve is raised however these fingers are spread by contact 70 with the lower end 19 of the tube, so as to permit free delivery of a succeeding mold from the tube. The sleeve movement is arranged to automatically control the delivery of the molds from the tube 3, and also to 75 effect their positive feed to the braiding fabric, at intervals determined by the braiding mechanism; to which latter it is operatively connected as indicated, by means of a vertical shaft 25, the lower end of which is arranged in gear with the carrier drive mechanism, and the upper end of which indirectly drives a sleeve-operating cam shaft 26. 80

The sleeve 20, which is normally raised upon the feed tube 3 by means of a spring 85 27, is lowered, as required, by means of a cam 28 on said shaft 26; said cam operating upon the outer end of a lever 29 which is pivoted intermediately, at 30, to the transverse carrier bar 5, while its inner end is 90 connected by a link 31 to the sleeve. The position of the pivotal connection 30 may be readily adjusted by means of slidable blocks 32, 32 on the carrier bar 5 and lever 29 respectively; and the cam 28 may also be varied in shape and form as desired; so as to produce movements of the sleeve 20 and its mold-engaging fingers 22 as required by the particular form and size of the molds. 95

In operation, a short portion of tubular fabric is first braided; the molds, conveniently strung upon a supporting stem 16, being then placed in the feed tube 3, with the wire stem extending through the closed tips of the feed fingers 24 into the braid, while 100 the molds are held back by said fingers. As 105

the cam 28 is rotated during braiding, the feed-finger sleeve is raised by the spring 27, thus spreading the fingers and permitting a downward movement of the molds until the 5 lowest one reaches the braiding point. Further rotation of the cam then lowers the sleeve, the fingers closing upon said mold and pushing it down into the forming braid until the latter has enough hold on the mold 10 to pull it along while covering it; after which the sleeve movements are repeated as required by the particular molds and their required spacing.

The preferred construction described may 15 obviously be modified in form and in relation to the machine, and certain features thereof be entirely omitted, without departing from the invention as defined in the claims.

20. What I claim is:—

1. A feeding attachment for tubular braiding machines comprising a centrally fixed mold feed tube, mold-feed fingers at the exit end of said tube, and means for 25 opening and closing said fingers and reciprocating the same at determined intervals.

2. A feeding attachment for tubular braiding machines comprising a centrally fixed mold feed tube having an axial supporting stem projecting through the exit 20 end thereof, mold-feed fingers at the exit end of said tube, and means for opening and closing said fingers and reciprocating the same at determined intervals.

3. A feeding attachment for tubular braiding machines comprising a centrally fixed mold feed tube, a sleeve slidable on said tube and provided with spring-pressed fingers pivoted thereto and adapted to pro-

ject beyond the exit end of said tube, and means for reciprocating said sleeve.

4. In combination with a tubular braiding machine having a transverse carrier bar, a tubular mold container carried by said bar, mold-feed devices at the exit end of said container comprising a sleeve slidable upon the latter, an operating lever for said devices pivotally carried by said bar, and a cam device for operating said lever arranged in gear with the braiding mechanism.

5. In combination with a tubular braiding machine having a transverse carrier bar, a mold container carried by said bar, mold-feed devices at the exit end of said container, an operating lever for said devices 55 pivotally pivoted to said bar, and a cam device for operating said lever arranged in gear with the braiding mechanism.

6. A feeding attachment for tubular braiding machines comprising a centrally 60 fixed mold feed tube having an axial mold supporting stem projecting through the exit end thereof and provided with a collapsible tip, and intermittently operated mold-feed devices at the exit end of said tube.

7. A feeding attachment for tubular braiding machines comprising a centrally fixed mold-carrier device provided with a spring tip, and intermittently operated mold-feed devices at the exit end of said carrier device.

In testimony whereof I affix my signature in presence of two witnesses.

ROBERT CARL RAHM.
